[57] ABSTRACT

A method of knitting a shaped panel for making up together with other panels into a garment; needles are taken out of action at the edges of the panel to reduce the number of wales in the panel to shape it, and knitted loops are held on the inactive needles whilst knitting continues, at a later stage, said inactive needles are brought back into knitting action again or the loops are cast off.

KNITTED GARMENT PANEL

This invention relates to the knitting of shaped panels for garments.

One method of producing a knitted garment comprises knitting shaped panels constituting parts of the garment and securing the panels together, for example by seaming, to form the garment. The panels are often knitted to the shape required on a fully fashioned flat bar knitting machine. Such machines normally have limitations with regard to the variety of patterns which can be knitted on them and an object of the present invention is to provide a practical and economical method of knitting shaped garment panels on a flat V-bed knitting machine having independently operable needles and on which the patterning potential can be greater than on a fully fashioned flat bar machine.

A method of knitting a shaped garment panel according to the invention includes the step of narrowing the panel by taking needles at one edge at least of the panel out of action whilst maintaining loops on the needles thus made inactive, knitting being continued on other needles, and bringing the said inactive needles back into operation to continue knitting, or to press off their loops to release the knitted panel from the machine.

The method can be carried out on a flat V-bed knitting machine having web-holding sinkers or having a presser foot, such as that described in the specification of published German Application P 19 56 190, serving in place of normal take down rollers and may also be carried out in suitable circumstances on other V-bed machines having take down mechanisms capable of exerting a downward force on the knitting which can be varied across the machine and/or during knitting. The invention may be carried out on other knitting machines with independently operable needles and a take down mechanism or alternative mechanism with suitable characteristics.

If part of the panel has to be widened, the widening can be effected by needle introduction at an edge or edges of the panel.

In one example of the method according to the invention the body panel shown in the accompanying drawing is knitted in rib knitting on a V-bed knitting machine having a presser foot as described in the aforementioned specification and a looper arrangement as described in the specification of published German Application P 20 59 094. Take down rollers are not used.

A length of rib knitting is cast on to the needles of the machine to commence knitting at the waist end of the panel. Casting onto empty needles can be effected without difficulty using the presser foot referred to above. Knitting is then carried out on the same number of needles until the number of courses required for the waist band 1 of the panel has been completed.

The garment panel is then widened by needle introduction at the edges of the panel to produce the portion 2 of the panel. In the present example, needles are introduced in pairs at the two edges of the panel. The introduction is effected by programming the patterning mechanism of the machine in such a way that the butts of four extra needles, are presented to a cam track in the cam box in each course in which widening is to take place.

The yarn carriers of the machine are arranged to move over a number of needles in excess of the number required to knit the widest part of the panel so that yarn

is available for newly operated needles as they are brought into action.

Of the four needles brought into action at each widening, two are at one end of the bank of previously active needles and two are at the other end. In knitting the present rib knitted panel, of each adjacent pair of needles brought into action, one needle is in one bed of the machine and one in the other.

After the widened portion 2 of the panel has been 10 knitted, a parallel-sided portion 3 of the panel is knitted up to the underarm position 4 and thereafter narrowing of the panel is commenced to produce the portion 5 of the panel.

Narrowing is effected, in the present example, by taking 15 out of action pairs of needles at the ends of the bank of active needles on the machine producing the stepped line seen along the edges 6 of the panel. Of the pairs of adjacent needles taken out of action, one is in one bed of the machine and one in the other. The needles are 20 taken out of action by programming the patterning mechanism of the machine in such a way that, in each course in which narrowing is to be effected, butts of two needles at each edge of the panel are removed 25 from the positions at which they can enter a cam track in the cam box of the machine. These needles are thus 30 made inoperative in such a way that the last loop formed on each of these needles is retained in the hook. The fact that loops are maintained in the hooks of needles not performing a knitting action whilst the knitting of the panel proceeds is indicated schematically at 7 in the drawing.

In the present example, to produce a Raglan style garment, narrowing is carried out every second course until the neck of the panel is reached. The programming mechanism is arranged to bring all the needles holding loops back into operation at this juncture, so that the previously inactive needles are raised by the cams to cast off their loops. No yarn is supplied to the needles at this stage in order that casting off may be effected and the loops on the active needles at the central region of the panel are cast off as well as the loops on the previously inactive needles. The finished panel then falls from the needles and the knitting of the next panel can be commenced immediately, the presser foot on 40 the machine enabling knitting to be commenced with empty needles to the full width required for the next panel.

Instead of casting off loops only when the knitting of the panel is complete, held loops can be cast off when 50 a substantial part of the panel has been completed and before further narrowing, creating additional held loops, is carried out. For example casting off may be carried out once or perhaps twice or more during the knitting of a panel.

55 Since no loops are cast off until all or a substantial part of the panel has been completed, no non-knitting traverses of the cam box are required in order to operate needles to cast off loops at frequent intervals during the knitting of the panel. The overall time taken to knit 60 a panel is thereby reduced.

Patterning and stitch effects can be incorporated in the panel according to the capabilities of the machine on which the panel is knitted.

65 Although the knitting of a panel in rib knitting has been described in detail, the method according to the invention can also be carried out in plain knitting. If desired a rib border can be knitted first on needles of two

opposed beds of needles before the loops on one bed are transferred to the opposite bed to continue in plain knitting.

Instead of casting off loops held on inactive needles when the panel is complete, with the result that garment panels drop individually from the machine, a succession of panels joined together can be knitted by supplying a draw thread or waste yarn to the still active needles which are knitting the narrow upper end portion of the panel when the previously inactive needles are again brought back into operation to cast off the held loops. One or more courses of draw thread or waste yarn can be knitted before knitting the first course of the next panel without need for widening the said draw thread or waste yarn courses before knitting the said first course.

In previous methods of knitting shaped panels, successively longer courses of draw thread or waste yarn have been knitted to widen the knitted fabric from the narrow upper portion of one panel to the longer first course of the next. In the present method the inclusion of such successively longer widening courses is not necessary.

What is claimed is:

1. A method of knitting a flat shaped panel for a finished garment in which the knitted wales run substan-

tially vertically, said method comprising the steps of knitting the panel on needles of a knitting machine with independently operable needles, narrowing at least a portion of the panel along at least one edge thereof by taking a plurality of needles serially out of action whilst maintaining loops of said panel on the needles thus made inactive, meanwhile continuing knitting of the panel on other needles of the machine, bringing said needles and only said needles which have been taken out of action serially back into action together, and casting off loops to release at least said portion of the panel from the needles.

2. A method according to claim 1 wherein said inactive needles are brought back into operation when the knitting of the panel has been completed.

3. A method according to claim 1 wherein needles rendered inactive whilst holding loops are brought back into operation together for casting off before completion of the panel and further needles at one edge at least of the panel are taken out of action whilst loops are maintained on said further needles, knitting of the panel being continued on other needles, said further inactive needles being brought back into operation together for casting off.
